United States Patent Office.

GEORGE W. ROTHROCK, OF MIFFLIN, PENNSYLVANIA.

Letters Patent No. 91,567, dated June 22, 1869; antedated May 25, 1869.

IMPROVED FOOT-COMFORTER.

The Schedule referred to in these Letters Patent and making part of the same.

To all whom it may concern:

Be it known that I, GEORGE W. ROTHROCK, of Mifflin, in the county of Juniata, and State of Pennsylvania, have invented a new and useful Improvement in Foot-Comforter; and I do hereby declare the following to be a full, clear, and exact description thereof, reference being had to the accompanying drawing, making a part of this specification, in which—

Figure 1 is a perspective view of my improved foot-comforter;

Figure 2 is a bottom view thereof; and

Figure 3 is a side view of the same, when the opposite halves are folded together for convenience in packing.

Like letters of reference indicate like parts in each.

The nature of my invention consists in the construction of a double-folding shoe or foot-comforter, with insulators on the bottoms of the soles. It is particularly, though not solely designed for the use of travellers in cars or other places where the heating is defective, during the cold seasons of the year. It is also so made, that while sufficiently capacious to receive both of the feet of the traveller, when unfolded, it can, at the end of the journey, or while changing cars, be folded together so as to be conveniently packed in a carpet-bag, or valise, or overcoat-pocket.

To enable others skilled in the art to make and use my invention, I will proceed to describe its construction and manner of use.

a is the "upper" of the shoe, made of any suitable material, preferably of some heavy woollen fabric, or other warm flexible article, such as will protect from cold the sides and top of the feet, the ankles, and, if made higher, as much of the limbs as the traveller may desire.

It is made to open and close by buttons, clasps, or straps or lacings, c, in any known manner.

b b' is a sole made of leather, India rubber, or other like material usually employed for such purpose, the opposite halves b b' being united by a crease or joint, e, such that they may be folded together, when not in use, for convenience in packing. The soles b b', if so desired, may be lined with any material which will protect against the cold.

On the bottoms of the soles b b' are insulators, d d', preferably of wood or other suitable material, such as may be a poor conductor of heat. These insulators are of such height that they will keep the soles b b' a little above the floor, and free from contact with the moisture or dampness of the car-floor.

As already stated, when not in use, the opposite halves of the shoe are folded together, as in fig. 3, the crease or joint e in the sole permitting this, and then can be conveniently stowed away in a valise, carpet-bag, or capacious pocket. The joint e may be made by creasing the leather of the sole, or by uniting the two halves, so as to give a folding joint.

What I claim as my invention, and desire to secure by Letters Patent, is—

A foot-comforter or shoe, having folding soles b b', and insulators, d d', one or more on each half sole, substantially as and for the uses above set forth.

In testimony whereof, I, the said GEORGE W. ROTHROCK, have hereunto set my hand.

GEO. W. ROTHROCK.
